GUY L. TINKHAM, OF DETROIT, MICHIGAN, ASSIGNOR TO GENERAL UTILITIES MFG. CO., OF DETROIT, MICHIGAN, A CORPORATION OF DELAWARE

PROTECTIVE DEVICE FOR WRINGER ROLLS

Application filed October 5, 1931. Serial No. 567,027.

This invention relates to a protective device for washing machine wringers to prevent the fingers of an operator being caught between the wringer rolls.

5 One object of my invention is to provide a protective device which is simple in construction, inexpensive to manufacture and install, and effective in operation.

Other and further objects of the invention will appear from the following specification taken in conjunction with the accompanying drawing, in which—

Fig. 1 shows a washing machine having a wringer equipped with a protective device of 15 my invention;

Fig. 2 is an enlarged vertical sectional view taken on line 2—2 of Fig. 1;

Fig. 3 is a perspective view of the protective device; and

20 Fig. 4 shows one of the springs to be hereinafter described.

In the drawing, 1 indicates the tub of the machine and 2 the wringer mechanism mounted above the tub in a manner for adjustment 25 about a vertical axis at one side of the tub as in machines of this general character.

The wringer mechanism comprises an outside frame 3 forming a support for a pair of upper and lower wringer rolls 4, 5, horizontally disposed on shafts 6, 7. The rolls are maintained in contact as shown in Fig. 2 by a suitable spring tension 8 so that power being applied to one roll will rotate both of them. In the drawings, I show the lower 35 roll as the driving one being connected with the electric motor of the machine through a suitable drive. The latter may include a clutch device having a control member 9 whereby the wringer mechanism may be connected to and disconnected from the motor whenever desired. The clutch device may be 40 of a character permitting reversibility of the wringer rolls, or a reversible electric motor may be used if desired, in which case a reversing clutch would not be employed.

The protective device of my invention comprises a pair of auxiliary or protective rolls 10, 11 arranged on opposite sides of the wringer mechanism in front of the wringer 50 rolls, as shown in Fig. 2. Rolls 10 and 11 extend along the full length of the wringer rolls where exposed through the frame 3 and are normally maintained in contact with the upper roll 4 by spring means to be presently 55 described. By this arrangement, roll 4 when

rotated rotates both protective rolls, the one on the front side of the wringer turning inwardly, while the one on the rear side of the wringer turns outwardly when the wringer rolls are rotated in the directions indicated by the arrows in Fig. 2. This provides a feed into the wringer over the protective roll 10 and a feed out of the wringer over the roll 11. A reversal of rotation of the wringer rolls reverses the direction of this feed. With 60 the protective rolls held in yieldable engagement with the wringer roll 4, the protective rolls will move out of contact therewith on the passing of any material between the rolls. The protective rolls will turn at this time in 65 the direction of the feed of the material as produced by the squeezing action of the wringer rolls thereon.

Being yieldably mounted, the protective rolls will also move away from the wringer 70 roll 4 should the fingers of the operator be inserted or caught between such rolls with no injury resulting because the protective rolls not being positively driven, will stop rotating and have no feeding action toward the 75 wringer rolls.

As shown in the drawing, the protective rolls on both sides of the wringer are sufficiently large in diameter to occupy the greater portion of the space between the 80 wringer rolls and thus guard entry into the pass between such rolls, except over the protective rolls. Moreover, the protective rolls terminate sufficiently close to the lower roll 5 to provide such small clearance between 85 them that the operator's fingers cannot be caught by the wringer rolls if inserted into such space. This clearance cannot be enlarged because the protective rolls being in contact with the wringer roll 4 cannot be 90 moved upward. While the clearance is small, it is sufficient for the protective rolls to be moved out of contact with the upper roll in the use of the wringer.

The protective rolls are revolvably mounted 100 on rods 12, 13, one for each roll. These rods are held in parallel relation with the axis of the wringer rolls by links 14, 15, there being a pair of links for each rod. The links are at the opposite ends of their respective rods 105 and are rigidly secured thereto. The links extend toward the axis of the lower wringer roll 5 and are pivotally mounted about the same. This is accomplished by having the shaft 7 of the lower wringer roll pass through 110

the links. The links for one rod overlap the links for the other rod where they are mounted on the wringer roll shaft.

The links of each pair are equal in length so that the distance between the axis of a protective roll and a wringer roll is uniform from end to end of the rolls. This maintains the rolls in parallel relation at all times and prevents displacement or canting of a protective roll to render it ineffective as a safety element or guard.

The spring means for normally holding the protective rolls against the upper wringer roll, and for returning the protective rolls to the wringer roll when moved away from the same, may take any form found suitable for the purpose. In the drawings, I have shown a stiff wire spring 16, one at each set of links. Each spring is preferably a single length of steel wire bent about rods 12, 13, and shaft 7 and under such tension as to constantly urge the protective rolls against the upper wringer roll. As shown in Fig. 4, the spring is shaped to have integrally connected sections, one for each protective roll, and provided with a loop 17 to fit about shaft 7.

When the wringer is reversed, the protective roll 9 on the rear side of the wringer becomes the feed in roll.

The details of structure and arrangement of parts shown and described may be variously changed and modified without departing from the spirit and scope of my invention, except as pointed out in the appended claims.

I claim as my invention:

1. The combination with a washing machine wringer having upper and lower wringer rolls, of a device to prevent the fingers of an operator being caught between the wringer rolls, comprising a protective roll arranged in the space between the wringer rolls on the feed in side of the wringer, means providing a pivotal mounting for the protective roll about the axis of the lower wringer roll, and means acting through the pivotal mounting for yieldably holding the protective roll against the upper wringer roll.

2. The combination with a washing machine wringer having upper and lower wringer rolls, of a device to prevent the fingers of an operator being caught between the wringer rolls, comprising a pair of protective rolls arranged on opposite sides of the wringer in the spaces between the wringer rolls, means providing a pivotal mounting for the protective rolls about the axis of the lower wringer roll, and means yieldably holding the protective rolls in contact with the upper wringer roll.

3. The combination with a washing machine wringer having a supporting frame and upper and lower wringer rolls therein, of a rod arranged on one side of the wringer

in front of the wringer rolls and extending along the same, links pivotally mounted at their inner ends on the frame and having a non-rotative connection at their outer ends with the rod for holding the same against rotation and in parallel relation to the wringer rolls, a protective roll revolvably mounted on said rod and located in the space between the wringer rolls to prevent the fingers of an operator being caught between them, and means yieldably holding the protective roll against the upper wringer roll.

4. The combination with a washing machine wringer having upper and lower shafts and wringer rolls thereon, of a rod arranged on one side of the wringer in front of the wringer rolls and extending along the same, links pivotally mounted at their inner ends on the shaft of the lower wringer roll and having their outer ends rigidly secured to said rod, a protective roll revolvably mounted on said rod and located in the space between the wringer rolls to prevent the fingers of an operator being caught between them, and spring means yieldably holding the protective roll against the upper wringer roll.

5. The combination with a washing machine wringer having upper and lower shafts and rolls thereon, of a pair of rods on opposite sides of the wringer in front of the wringer rolls and extending along the same, a pair of links for each rod, said links having their outer ends rigidly secured to their respective rods and their inner ends overlapping and pivotally mounted on the shaft of the lower wringer roll, and a pair of protective rolls, one revolvably mounted on each rod and located in the spaces between the wringer rolls, and spring means drawing the protective rolls toward each other and yieldably holding them against the upper wringer roll.

6. The combination with a washing machine wringer having a support and upper and lower wringer rolls therein, of a device to prevent the fingers of an operator from being caught between the wringer rolls, comprising a pair of protective rolls arranged on opposite sides of the wringer in the spaces between the wringer rolls and extending along the same, a pair of rods, one for each protective roll and on which the protective rolls are rotatably mounted, a pair of links for each rod, said links having their outer ends connected to their respective rods and their inner ends pivotally mounted on the support, whereby the protective rolls may have movement toward and from the wringer rolls, and spring means acting on the rods through the links for drawing the protective rolls toward each other and yieldably holding them against the upper wringer roll.

In witness whereof, I hereto affix my signature.

GUY L. TINKHAM. 130
